UNITED STATES PATENT OFFICE.

PERRY W. KERR, OF SEATTLE, WASHINGTON.

NON-REFILLABLE BOTTLE.

1,269,456.

Specification of Letters Patent. Patented June 11, 1918.

Application filed December 22, 1918. Serial No. 68,183.

To all whom it may concern:

Be it known that I, PERRY W. KERR, a citizen of the United States, and a resident of Seattle, in the county of King and State 5 of Washington, have invented a certain new and useful Invention in Non-Refillable Bottles, of which the following is a full, true, and exact specification.

My invention relates to improvements in 10 non-refillable bottles and has for its principal object, to provide a bottle and stopper which may be readily emptied but cannot be refilled no matter in what position it may be turned. The advantages of a non- 15 refillable bottle which is cheap of manufacture and easy to assemble are apparent to all.

Other objects will appear as my invention is more fully explained in the following 20 specification, illustrated in the accompanying drawings and pointed out in the appended claim.

Figure 1 is a central cross section of my bottle and stopper. Fig. 2 is a sectional 25 plan on line α — α of Fig. 1.

Referring more particularly to the drawings, numeral 1 indicates the neck of a bottle which is usual except for a pair of opposite recesses 2. A stopper 3 fits the neck 30 of the bottle tightly and is held in place by spring actuated catches 4 which project from recesses 5 in the stopper into recesses 2 in the neck 1 of the bottle. Stopper 3 is cored as at 6 and 7, is concaved on the 35 lower end as at 8 and has a straight central opening 9 which extends from the top of the stopper downwardly and connects cores 6 and 7 to the concaved portion 8. Core 6 is cylindrical in form and has a transverse 40 baffle 10 which is integral with the stopper. Core 7 is hemispherical with the flat side uppermost and has a hemispherical float 11 centrally positioned within it. The stopper has guide pegs 13 above the float 11. Pegs 45 13 are hooked over the top float 11. A flexible chain or cord 14 hangs from the lowest extremity of float 11, passes through a wire eyelet yoke 15 and has a large ball 17 at-

tached to it below the yoke 15. The float 11 is shown located centrally in core 7 in 50 the figure but would actually rest upon the bottom of the core. The pegs 13 limit the upward movement of the float. It will be readily seen that the contents of the bottle may be easily poured from the bottle. 55 When it is attempted to refill the bottle while upright, the force of the liquid against the float holds it down in a closed position. When it is attempted to fill the bottle when in an inverted or sidewise position the action of the liquid tends to float the float 11 into a closed position and the weight of the ball causes a tension in cord 14 which also tends to close the float. The baffle plate 10 prevents tampering with the float. The concaved bottoms 8 and a rim 16 assist in emptying by preventing the ball from rolling into core 6.

While I have shown a particular form of embodiment of my invention, I am aware 70 that many minor changes therein will readily suggest themselves to others skilled in the art without departing from the spirit and scope of the invention, and I therefore desire to avoid being limited to the exact form shown and described except as pointed out in the appended claim.

Having described my invention, what I claim as new and desire to protect by Letters Patent, is—

In combination, a bottle, a stopper formed with a vertical passage throughout its entire length and interrupted by an upper cylindrical chamber and a lower hemispherical chamber, a transverse integral baffle 85 extending centrally across the cylindrical chamber, and forming adjacent the sides of the latter lateral passages, a hemispherical float valve located in and of less diameter than the diameter of the hemispherical chamber, inclined guides extending upwardly from the bottom of the hemispherical chamber and turned inwardly at their upper ends, to engage and limit the float valve to a position below and spaced from 90 the upper wall of the hemispherical chamber.

to prevent closing of such vertical passage, the upper ends of the guides terminating below the top of the hemispherical chamber, a cord depending from the bottom of the float 5 valve and below the bottom of the cork, a weight attached to the lower end of the cord, a yoke extending inwardly from the

walls of the vertical passage and extending below the bottom of the cork, said yoke having a central opening through which the 10 cord passes, and means between the cork and the bottle to secure said cork in fixed position.

PERRY W. KERR.
